UNITED STATES PATENT OFFICE.

PETER FRANTZ, OF STERLING, ILLINOIS, ASSIGNOR TO FRANTZ MANUFACTURING CO., OF STERLING, ILLINOIS, A CORPORATION OF ILLINOIS.

DOOR CATCH TO HOLD THE DOOR OPEN.

1,408,577.

Specification of Letters Patent.

Patented Mar. 7, 1922.

Application filed March 28, 1919. Serial No. 285,876.

To all whom it may concern:

Be it known that I, PETER FRANTZ, a citizen of the United States of America, and a resident of Sterling, county of Whiteside, 5 State of Illinois, have invented a certain new and useful Improvement in Door Catches to Hold the Doors Open, of which the following is a specification.

This invention relates to devices for holding a door in open position, and more particularly to devices of this kind which are adapted for use on garage or barn doors, or for similar purposes.

Generally stated, the object of the invention is to provide a novel and simple device, of this general character, which can be inexpensively manufactured, which will be strong and serviceable in use, and which will be more satisfactory than the devices 20 heretofore employed for this purpose.

It is also an object to provide certain details and features of construction tending to increase the general efficiency and the desirability of a door catch or holder of this particular character.

To these and other useful ends the invention consists in matters hereinafter set forth and claimed, and shown in the accompanying drawings, in which—

30 Fig. 1 is a plan of a door equipped with a catch or holding device embodying the principles of the invention, showing the adjacent portions of the door frame in horizontal section, and showing the door in open position.

35 Fig. 2 is a similar view showing the door closed.

Fig. 3 is a front elevation of the structure shown in Fig. 1, viewed at an angle of forty- 40 five degrees to the length of the catch or holding device which holds the door in open position.

Fig. 4 is a side elevation, on a larger scale, of the end of the holder which has the 45 catch.

Fig. 5 is a horizontal section on line 5—5 in Fig. 4.

Fig. 6 is a longitudinal section of the pivoted end portion of the device.

50 Fig. 7 is a transverse vertical section on line 7—7 in Fig. 4.

Fig. 8 is a plan of the end portion shown in Fig. 6.

Fig. 9 is a perspective of the bracket by which the device is pivoted on the door.

As thus illustrated, the door 1 may be hinged to the door-frame 2 in any suitable or desired manner. A bracket plate 3 is secured to the upper portion of the door, in any suitable manner, on the inner surface 5 of

thereof. A long arm 4 formed of sheet metal and made hollow, so that its interior is open at the bottom, and whereby it is of inverted U-shape in cross section, is formed at one end with integral portions 5 which engage the openings 6 in the ears 7 of said bracket plate.

A long locking bar 8 is pivoted at 9 within the arm 4, this pivot 9 being nearer the pivotal portions 5 than the other end of the arm, so that the notches 10 formed in the side walls of the arm near its free end portion normally expose the free end of said bar.

A chain 11 is attached at 12 to the shorter end portion of said bar 8, whereby the longer end of the bar may be pulled 75 upward. A stationary bracket plate 13 is secured to the under side of the door-frame, in about the position shown, and is provided with a guide opening 14 having side notches 15, and the arm 4 slides endwise in said opening when the door is opened and closed.

The free end portion of the arm is provided with a sort of head having a depending portion 16 which latter will engage the lower edge portion of the opening 14 and thereby 80 prevent the complete withdrawal of the arm from the plate 13, when the door is opened.

In other words, the head formed by the depending portion 16 and the upper portion 17 at the end of the arm is too large to pass 85 through the opening 14, when the parts are in working relation to each other; but in assembling the different elements, and before the parts are secured to the door and the door-frame, the plate 13 is turned side- 90

wise until the portions 16 and 17 can pass through the notches 15, and then the plate is turned around so that the arm 4 will rest 95 edgewise upon the lower edge of said opening 14 in the stationary bracket plate.

When the door is opened, the arm 4 slides outwardly through the opening 14, until the portion 16 strikes the lower edge of said opening, and the end of the bar 8 then drops below said edge at the opposite side of the 100 plate, so that this edge portion of the plate

is held between the portion 16 and the adjacent end of the pivoted bar. It will be seen that the notch 10 is long and sloping at one side, so that the arm 4 will move downward 5 a little before the portion 16 strikes the lower edge of the opening 14, the pivotal portions 5 being slightly loose in the bracket plate 3 for this purpose. This will lock the door in open position, inasmuch as any 10 effort to close the door will be resisted by the bar 8 which engages the lower portion of the bracket plate 13, thus effectively holding the door in open position. When it is desired to close the door, a pull on the chain 15 11 will lift the longer end of the bar 8 out of engagement with the lower portion of the bracket plate 13, so that the arm 4 can then slide endwise in the opening 14, in a manner that will be readily understood. When the 20 door is opened, the door holder occupies the position shown in Fig. 1, and when the door is closed, the catch or holding device then occupies the position shown in Fig. 2. It will be seen, of course, that the bracket plate 25 13 can be positioned as shown in the drawings, or that it can be turned and secured in a position which will bring it more nearly at right angles to the arm 4 when the door is open, the opening 14 being much wider 30 than the thickness of the arm, so that the latter can swing sidewise in said opening, as well as move endwise therein.

With this construction, therefore, the arm 4 merely slides back and forth endwise in the 35 opening 14, and the unlatching or releasing of the door is accomplished merely by operating the bar 8 which is enclosed within said arm. The bar 8 can be made light enough to be easily lifted, when it is desired 40 to close the door, and at the same time of sufficient stiffness to serve the desired purpose. This bar can be quite thin, in fact, without danger of bending or buckling, because it is enclosed between the two side 45 walls of the arm 4, which latter serves as a housing for said bar.

It will be understood that the door can be provided with spring hinges, or with

springs of any kind, if desired, to automatically close the door after it is released 50 from its open position.

What I claim as my invention is:—

1. In a device for holding a swinging door in open position, the combination of an arm, means to pivotally mount the arm on the 55 swinging door, so that said arm may swing horizontally relatively to the door, a guide secured to the stationary frame of the doorway, said arm sliding endwise in said guide and swinging horizontally and relatively 60 thereto, under the top of the doorway, when the door is opened and closed, a latch movably mounted on said arm to engage said guide, thereby to hold the door open, and means depending from said arm and adapted 65 for controlling said latch to release the door from open position, so that the arm may slide endwise through the guide to permit closing of the door.

2. A structure as specified in claim 1, said 70 arm being formed from sheet metal to provide a hollow interior therefor, and said latch comprising a long bar disposed within said hollow arm, and a pivot for supporting the bar at a point between the door and the 75 middle portion of the bar, whereby the longer end of the bar tends to gravitate into latching position when the door is opened, said guide having this lower portion formed to engage this end of the bar, and said controlling means being attached to the shorter end of the bar, whereby the longer end of the bar is lifted to release the door from the open position thereof.

3. A structure as specified in claim 1, said 85 arm being of sheet metal and formed with a head having a depending portion to engage the guide, thereby to limit the opening of the door, and said guide having means to permit the complete withdrawal of the arm 90 therefrom, by relative displacement of the guide and arm sufficiently to permit said head to pass out from the guide, substantially as shown and described.

PETER FRANTZ.
